[57] CLAIM

The ornamental design for a putting aid, as shown and described.

DESCRIPTION

FIG. 1 is a perspective view of a putting aid showing our new design;

FIG. 2 is a top plan view thereof;

FIG. 3 is a bottom plan view thereof;

FIG. 4 is a left side elevation view thereof, the right side view being identical;

FIG. 5 is a front end elevation view thereof, the rear end view being identical;

FIG. 6 is a cross section view taken along section line 6—6 of FIG. 2;

FIG. 7 is a perspective view of a second alternate embodiment; and,

FIG. 8 is a perspective view of a third alternate embodiment.

The broken line showing of the golf ball and club head in FIG. 1 is for illustrative purposes only and forms no part of the claimed design.

FIG. 1
